UNITED STATES PATENT OFFICE.

FRANK E. WARNER, OF WATERBURY, CONNECTICUT, ASSIGNOR TO SCOVILL MANUFACTURING COMPANY, OF WATERBURY, CONNECTICUT, A CORPORATION OF CONNECTICUT.

TACK-FASTENED STUD FOR SNAP FASTENERS.

Application filed July 23, 1927. Serial No. 207,961.

The object of this invention is to provide a snap-fastener member, such as a stud or head, with means by which the member may be set by application thereto of a tack or similar driven device, without liability to tipping.

The invention consists of a snap-fastener member, having located within it an element which frictionally engages the shank of the tack and also embraces it near its point, in such way that the snap-fastener member is securely attached to an article and liability to tipping is prevented, as I will proceed now to explain more fully and finally claim.

In the accompanying drawings illustrating the invention, in the several figures of which like parts are similarly designated, Figure 1 is a top plan view, and Fig. 2 is a vertical section of the shell of a non-resilient stud or head member of a snap-fastener. Fig. 3 is a top plan view, Fig. 4 is a bottom plan view and Fig. 5 is a vertical section of the tack-engaging element. Fig. 6 is a bottom plan view and Fig. 7 is a cross-section of the centrally depressed back of the stud or head. Fig. 8 is a top plan view and Fig. 9 is an elevation of one form of attaching member. Fig. 10 is a vertical section of the assembled stud or head, and Fig. 11 is a vertical section showing the parts set upon a substance.

Illustrating one embodiment of the invention, the shell is composed of a non-resilient knob-like portion 1, adapted to engage the complementary resilient socket member of a snap-fastener, and it has a laterally extending base 2 provided with a down-turned peripheral flange 3. Within this shell is placed the tack-engaging element 4, composed of a single piece of steel or other hard metal, bent to form a base 4' which is provided with an angular or other shaped hole 5, surrounded by the jagged edges 6 made by the hole-piercing tool. The ends 7 and 8 of the piece of steel are curved longitudinally and transversely and bent upwardly and converged to form the upstanding element 9, in line with the hole 5.

This tack-engaging element is placed within the shell, as indicated in Figs. 10 and 11, and then the centrally depressed back 10 is placed within the flange 3 and the flange closed down over its rim, as indicated in Figs. 10 and 11, whereby the tack-engaging element is securely

clamped between the shell and back, as shown in Figs. 10 and 11, and the back of the shell closed. This back 10 has a hole 11 of the same conformation as the hole 5 and in line therewith and having the jagged edges 12 made by the hole-piercing tool.

The preferred shape of the holes 5 and 11 is triangular, as shown, as this shape gives very satisfactory frictional grip on the shank of the fastening tack, but the invention is not limited to the shape of the hole excepting as claimed; nor is it necessary, although preferable, that the holes 5 and 11 be of the same shape and conformation.

The fastening device, as shown in Figs. 8, 9 and 11, may be a tack, having a head 13 and a pointed shank 14 of any usual or approved construction. It is preferred that the fastening device should be pointed so as to pierce its own hole through the article to which the stud or head is to be applied.

As represented in Fig. 11, the article 15 has the stud or head placed on one side and the tack entered thereto from the other side, sufficient pressure being used to force the tack through the article and through the holes 11 and 5, both of which holes are of slightly less dimensions than the shank of the tack so as to ensure sufficient frictional engagement with the tack and the tack-engaging element 4 to effect a stable engagement of the tack with the stud or head and prevent accidental separation of the two. The pointed end of the tack extends up between the upstanding ends 7 and 8 in such manner as to prevent tipping and to keep the parts in alignment, as indicated in Fig. 11.

It will be observed that the point of the tack 90 is not upset, and, therefore, it is unnecessary, from a securing or setting point of view, that the end of the tack should come in contact with the inner surface of the knob of the stud or head.

With the construction described, it is unnecessary to provide any springs or other locking device than the back, and particularly the tack-engaging element 4, and to this extent the construction is greatly simplified and the manufacturing costs reduced.

While the invention is shown as applied to a non-resilient stud or head, it is applicable to a resilient stud or head.

The construction is susceptible of variations in detail within the principle of the invention and the claims following.

What I claim is:—

- 5 1. A snap-fastener member, having a shell, and a tack-engaging member arranged within said shell and comprising a base having a hole through which the tack passes and by which it is frictionally engaged, and upstanding end members curved longitudinally and transversely to conform to the shank of the tack and converging to engage the leading end of the tack to prevent tipping.
- 10 2. A tack-fastened stud for snap-fasteners, having a shell and an internal one piece hard metal tack-engaging member comprising a base having a jagged edge hole through which the tack passes and by which it is frictionally engaged, and upstanding end members shaped to conform to the shank of the tack and to engage its leading end to prevent tipping.

3. A tack-fastened stud for snap-fasteners, comprising a knobbed shell having a flanged element, a one piece tack-engaging element 25 having a base provided with a jagged edge hole and upstanding converging ends and located within the shell, and a back secured to the flanged element and clamping the tack-engaging element in the shell.

30 4. A tack-fastened stud for snap-fasteners, comprising a knobbed element and a flanged element, an internal tack-engaging element having a base provided with a hole and upstanding converging ends, and a back secured to the flanged element and clamping the tack-engaging element in the shell, the back having a hole in line with the hole in the tack-engaging element and both of the holes being jagged.

40 In testimony whereof I have hereunto set my hand this 22 day of July A. D. 1927.

FRANK E. WARNER
